DECORATIVE BUCKLE

William L. Myers, Newark, N. J.

Application May 13, 1937, Serial No. 142,329

8 Claims. (Cl. 2—245)

The invention relates to decorative buckles, and more particularly to a metal buckle which may be applied to shoes, handbags and various other types of feminine apparel or accessories.

5 Prior to my present invention, great difficulty has been experienced in providing buckles of the type to which the invention relates, which can be conveniently applied to various articles in a manner which will avoid accidental loosening of the buckle plate or its escape from the portion of the buckle by means of which it is attached to the article.

Ordinarily, as shown in Patent No. 1,738,605 to W. L. Myers and George D. Harrison, a spring 15 clip is attached by sewing or by wire stitching to the article, the tongues of this clip having a wide range as to form and co-operate with a strap spaced from the back of the plate, said clip and said strap being provided with co-operating 20 nubs and recesses for preventing sliding movement of the plate in relation to the clip.

The applying of the clip shown in said Letters Patent to the shoe or other article involved a difficult manufacturing process and precluded 25 the use of a sewing machine for the purpose. Consequently, the stitching in different articles was irregular in thickness, which condition interfered with a proper engagement of the rolls forming the jaws of the clip with the back strap 30 of the face plate. This, at times, resulted in an improper gripping of the plate strap by the roll jaws of the clip, so that there was frequent displacement or loss of the decorative buckle plates. There was also likelihood of creepage of the 35 buckle plate in relation to the jaws of a clip, resulting in a loss of adjustment of the buckle plate and at times in its escape from the clip.

With the above conditions in mind, I have provided a buckle structure in which the strap upon 40 the plate of the buckle may be readily engaged with the roll jaws of a clip secured to the article in a manner to not only firmly hold the plate in position upon the article, but to prevent any longitudinal shifting of the plate in relation to the jaws of the clip.

To secure the desired effect, the strap upon the buckle plate is made of a width and a thickness 45 to pass between oppositely disposed jaws upon the clip, and to place and maintain these jaws under tension sufficiently great to develop and maintain a firm gripping action of the jaws upon the strap at all times. This tensioning of the jaws of the clip is supplemented by the formation of abutments upon the strap engageable by the ends of the jaws so as to preclude any

possible slippage of the jaws in relation to the strap.

I also provide a clip which is so constructed as to provide areas engageable with the presser foot of a sewing machine when attaching the 5 clip to the article, thus permitting the use of such a machine in permanently securing the clip to the article. Adjacent these areas the width of the clip is reduced, such reduced or neck portions being positioned beyond the points of 10 engagement of the jaws with the strap, so that the stitching will not interfere with the engagement of the strap with the clip in assembling the buckle upon an article of the character above referred to.

By forming the clip in the manner above described, and by using a strap provided with abutments engaging the ends of the jaws of the clip, the number and arrangement of the jaws upon the clip may be varied, although it is essential 20 that at least two opposed jaws be employed in order to secure the desired gripping action thereof upon the strap of the plate.

With a buckle embodying the invention, the jaws of the clip so firmly engage the strap upon 25 the decorative plate that this plate can be removed from the article only by means of a tool, thus preventing accidental loss of the plate under all conditions of use as a result of the escape 30 of the strap from the roll jaws. While the gripping action of the jaws is great, there is always 35 possibility of displacement of the decorative plate by relative movement between the securing strap and the jaws of the clip, the abutments upon the strap being used to prevent such relative movement which, even though it would not permit a complete removal of the plate, might nevertheless result in a loss of adjustment of the latter which might be objectionable to the 40 user of the article.

By affording a strong gripping action of the jaws upon the strap of the plate, and by preventing a relative movement of these two parts, I am enabled to provide a buckle structure in which accidental shifting or escape of the plate 45 relative to, or from the jaws is prevented.

The invention consists primarily in a decorative buckle embodying therein a clip having oppositely disposed rolled spring jaws and provided with means whereby it may be attached 50 to an article, and a decorative face plate having on the back thereof a strap spaced from said plate and of a width and thickness to pass between and tension said jaws, the portion of said strap presented toward said plate being of reduced 55

width as compared with the outwardly presented surface thereof, said strap being provided with abutments engageable with an end of the jaws to prevent relative longitudinal movement of 5 said strap and said jaws; and in such other novel features of construction and combination of parts as are hereinafter set forth and described, and more particularly pointed out in the claims here-to appended.

10 Referring to the drawing,

Fig. 1 is a perspective view of an article of 15 footwear having the clip of the buckle attached thereto;

Fig. 2 is a perspective view of one form of the 15 clip upon an enlarged scale;

Fig. 3 is a perspective view of the back of the buckle proper;

Fig. 4 is a cross sectional view upon the line 4—4 of Fig. 5;

20 Fig. 5 is a section on the line 5—5 of Fig. 4;

Fig. 6 is a rear view in perspective of the back of a plate showing a modified form of strap;

Fig. 7 is a perspective view of the back of a 25 plate showing a still further modified form of strap;

Fig. 8 is a perspective view of the clip used with the plate shown in Fig. 7; and

30 Fig. 9 is a back view of the assembled buckle embodying the plate and clip shown in Figs. 7 and 8.

Like numerals refer to like parts throughout the several views.

While, in the accompanying drawing, the invention is illustrated as being applied to a decorative fitting for a shoe, it is obvious that the spring clip may be applied to any other article of apparel or accessory by merely adapting the form of the decorative plate to the article to which it is to be applied. It is also obvious that 35 the dimensions of the clip and of the decorative plate may be varied to adapt the buckle to the particular conditions of use for which it is intended.

40 While the article herein referred to is generally designated in the trade as a buckle, it ordinarily is not used to secure different objects together, the usual function of a buckle.

45 The buckle of the application embodies therein a spring metal clip consisting of a base 10 having one or more pairs of spring jaws formed by rolling lateral extensions upon the base, these jaws being indicated at 11 and 12. At the opposite ends of the base 10 are enlarged ends 13 and 14 forming areas for the engagement of the 50 presser foot of a sewing machine with the clip, these ends being connected with the base 10 by reduced portions or necks 15 and 16 about which the stitches used in securing the clip to an article pass. It will be noted that these necks 15 55 and 16 are positioned beyond the ends of the spring roll jaws 11 and 12 so as to be conveniently accessible when sewing the clip to the article to which it is to be attached.

60 While other means may be employed for securing the clip to an article, the use of a sewing machine is preferable since this operation is thus made simple and inexpensive and affords no hard projections from the back of the article to which the clip is attached. When the buckle is used 65 upon shoes, this feature is particularly desirable, although for handbags and other accessories the use of staples or eyelets would not be objectionable.

70 The reduced necks 15 and 16 afford means 75 whereby a clip may be attached to an article in

a manner to prevent slippage of the clip in relation to the article, since the securing means passing about said necks are positioned between the ends of the body 10 and the enlarged ends 13 and 14.

5 The decorative face plate 17 may take any desired form and have any desired artistic finish upon the front thereof. This plate is provided with a back strap 18, the angularly bent ends 19 of which, as shown in Figs. 3 to 6, are welded, 10 brazed or otherwise secured to the back of the plate. This back strap 18 is preferably formed of a flat wire of approximately .060 of an inch in thickness, having the opposite edges thereof bevelled as shown at 20, the bevel extending from the edge at the outer face of the wire inwardly of the strap and towards the plate. The thickness of this strap is approximately one-half the diameter of the loops 11 and 12, and is of a width 15 approximating the distance between the centers of the loops of each pair of jaws, so that when inserting the strap between the jaws, these jaws must flex outwardly to a considerable extent.

The width and thickness of the strap 18 limits reflexure of said loops so as to ensure a firm 20 gripping of the side edges of the strap by the rolls forming the loops. The strap 18 is spaced by its ends 19 from the face plate a distance greater than the diameter of the rolled spring 25 jaws co-operating therewith. Hence, the spring 30 jaws are held under tension at all times, thus developing a gripping action sufficiently strong to eliminate all possibility of the strap 18 escaping 35 from between the jaws of each pair.

The plate 10 and all parts appurtenant thereto 35 including the jaws 11 and 12 are made of thin gauge spring metal, and the diameter of each loop is approximately twice the thickness of the stock in the strap 18.

The bent ends 19 of the strap 18 are of a 40 length to space the portion of said strap engageable by the spring jaws well away from the back of the plate, so that no restraint is placed by engagement of any part of the jaws therewith which would prevent the movement of the jaws 45 in developing the gripping action above referred to.

45 By beveling the edges of the flat wire forming the strap 18, this strap may be positioned between opposed jaws 11 and 12 by inserting 50 one edge of the strap close to the body 10 of the clip and below the portion of one of the loops 11 or 12 of each pair converging outwardly towards the base 10, and then by a lateral rolling action, forcing the other edge of the strap past 55 the opposed loop 12 or 11. In so doing, both jaws are flexed to the desired extent, and the engagement of the jaws of each pair adjacent the greatest diameter thereof with the edges of the strap will develop the desired frictional engagement to prevent the strap being withdrawn from 60 between the jaws by hand or escaping accidentally from the jaws.

65 The engagement of the rounded surface of the jaw with the edge of the strap develops a strong camming action when pressing one side of the strap toward the jaws, both jaws thus yielding to permit the passage of the strap therebetween. Instantly that the edge of the strap passes the horizontal diameter of the jaw 12, this jaw flexes 70 inwardly of the strap and engages the bevelled portion thereof, the other jaw having a similar action so as to firmly grip the edges of the strap at the horizontal diameter of each jaw.

75 By beveling the edges of the flat wire strap, 75

the resistance to the turning movement of the strap is largely from the roll jaw 12, although there will be some though much less resistance from the roll jaw 11, which, however, will be below the horizontal diameter of this roll. With this action, the thrust upon one of the jaws, as 11, is upwardly and outwardly, while the thrust upon the other jaw is downwardly and outwardly. Immediately, however, that the edge of the strap 10 co-operating with the jaw 12 passes the horizontal diameter of this jaw, both jaws are permitted to reflex, and the portion of the jaw immediately below such horizontal diameter and between it and the bottom of the roll, grips the 15 edges of the strap.

By bevelling the edges of the strap in the manner described, a portion of each edge of the strap is positioned below the horizontal diameter of the jaws. These jaws, being curved, have 20 only a lineal contact with the strap. The extreme edges of the strap, however, positioned as they are, make the removal of the strap from the jaws extremely difficult because the excess width of the strap afforded by the bevel at either 25 edge requires a greater flexure of one of the jaws in removing the plate than would be required if the strap had straight edges and were of less width.

While the grip of the jaws on the edges of the 30 strap is sufficiently strong to practically eliminate all possibility of the escape of the plate from the clip, it is possible that the strap may have sliding movement longitudinally of the jaws, thus giving an irregular finish to the article to which 35 the buckle is applied. To avoid this condition, I provide the strap 18 with an abutment or abutments engaging one or both ends of the roll jaw, so that any such sliding movement is prevented.

In the form of the invention shown in Figs. 1 40 to 5, this abutment is in the form of a small block 21 secured centrally of the length of the strap 18, the width of this block being substantially the same as the distance between the ends of the jaws 11 and 12 of the two sets of jaws. This block 45 is positioned upon the face of the strap presented towards the plate 17, so that as shown in Fig. 4, when the strap is engaged by the jaws, the block will bear upon a substantial portion of the circumference of each jaw. There is a free sliding fit between the jaws and this block, but the presence of the jaws prevents movement of the strap and the plate 17 carried thereby in either direction. The downturned ends 19 of the strap act 50 as abutments opposed to the edges of the block 21, and if desired, these downturned ends may be relied upon as abutments supplementing the block 21 or acting independently of this block.

The length of the jaws 11 and 12 is such as to 55 pass freely between the block 21 and the turned ends 19 of the strap, so that the block 21 alone or in conjunction with the downturned ends will serve to accurately locate the position of the plate 17 by means of the jaws 11 and 12.

In the form of the invention shown in Fig. 6, 60 a strap 22 is used having right angular ends 23 and provided with notches 24 and 25 cut in the opposite edges thereof, leaving a central portion 26 corresponding in function with the block 21. The edges of the strap within the recesses 24 and 65 25 are perpendicular to the surface of the strap, and with this form of the invention, the jaws must be spaced closer together than in the form of the invention shown in Figs. 1 to 5. The advantages of the bevelled edges of the wire 70 75 are not present with the use of a strap as shown

in Fig. 6, although a strong grip can be secured with this construction of strap, and sliding of the strap in relation to the jaws is prevented.

In the forms of the invention shown in Figs. 1 5 to 6, two sets of jaws are used, which gives 5 a very strong gripping action because of the length of the lineal contact between each jaw and the edge of the strap. With some ornaments, however, the use of a strap having ends bent at an angle is not desirable or feasible, or it is desirable to use only a single pair of jaws.

Such a construction is illustrated in Figs. 7 to 9, in which a strap 27 is in arcuate form and has side recesses 28 and 29 substantially centrally of the length thereof forming opposed shoulders 30 15 and 31 engageable with the ends of a single pair of jaws 32 and 33 upon a spring clip, the construction of which in other respects is as shown in Fig. 2.

The jaws 32 and 33, as in the form of the invention shown in Fig. 2, are in the form of rolls of a greater length, however, than as shown in Fig. 2, and positioned more closely together because of the reduced width of the strap due to the presence of the recesses 28 and 29. This embodiment of the invention is particularly adapted for use with plates 17 of smaller size than those used in the other forms of the invention, and permits the setting of opposite edges of the plate closer to the article to which it is attached.

While the strap 27 is made of flat wire rectangular in cross section without bevelled edges, with the use of slightly longer jaws a highly effective gripping action can be secured.

In all forms of the invention shown, the effectiveness of the attachment means of the buckle plate to the article, results from the co-operation of roll spring metal jaws of a clip so formed as to be capable of attachment to an article prior to the mounting of the plate thereon, combined with 40 a strap, the construction of which is such as to require the tensioning of the spring jaws when mounting the strap in said jaws and the engagement of the edge of this strap with the jaws at a point closely adjacent the horizontal diameter of 45 the jaws. With this arrangement, the inherent elasticity of the jaws is relied upon at all times to develop the gripping action, these jaws necessarily being flexed when inserting the strap therebetween, and the reflex action of the jaws being 50 limited by the strap, so that at all times after the application of a plate to an article by means of the clip, the jaws will be maintained under a sufficiently high tension to develop the desired gripping action.

In conjunction with the foregoing, the plate or buckle strap is so formed as to afford abutments with which the ends of the jaws engage so as to prevent slippage of the plate in relation to the jaws and to an article to which the plate is attached by means of the jaws.

It is not my intention to limit the invention to the precise details of construction shown in the accompanying drawing, it being obvious that such may be varied to adapt the invention to different sizes and shapes of buckle plates and of different articles to which said buckle plates are to be applied.

Having described the invention, what I claim as new and desire to have protected by Letters 70 Patent, is:—

1. A decorative buckle embodying therein a clip having oppositely disposed rolled spring jaws and provided with means whereby it may be attached to an article, and a decorative face plate 75

having on the back thereof a strap spaced from said plate and of a width and thickness to pass between and tension said jaws, said strap being provided with abutments engageable with an end 5 of the jaws to prevent relative longitudinal movement of said strap and said jaws the portion of said strap presented toward said plate being of reduced width as compared with the outwardly presented surface thereof.

10 2. A decorative buckle embodying therein a clip having oppositely disposed rolled spring jaws and provided with means whereby it may be attached to an article, and a decorative face plate having on the back thereof a strap spaced from 15 said plate and having a maximum width greater than the spacing of said jaws from each other, and a thickness of substantially one-half the diameter of the roll forming said jaws, the portion of said strap presented toward said plate being 20 of reduced width as compared with the outwardly presented surface thereof, whereby said jaws will be outwardly flexed when passing said strap between same, and the reflex action of said jaws will be limited by engagement with the edge of 25 said strap so as to maintain said jaws under a constant tension.

3. A decorative buckle embodying therein a clip having oppositely disposed spring rolled jaws and provided with means whereby it may be attached to an article, and a decorative face plate having on the back thereof a strap spaced from 30 said plate and having a maximum width greater than the spacing of said jaws from each other, and a thickness of substantially one-half the diameter of the roll forming said jaws, the portion of said strap presented toward said plate being of reduced width as compared with the outwardly presented surface thereof, whereby said jaws will be outwardly flexed when passing 35 said strap between same, and the reflex action of said jaws will be limited by engagement with the edge of said strap so as to maintain said jaws under a constant tension, said strap being provided with abutments engageable with an end of 40 45 the jaws to prevent relative longitudinal movement of said strap and said jaws.

4. A decorative buckle embodying therein a clip having two pairs of oppositely disposed rolled spring jaws, the jaws of each pair being spaced from those of the other pair, and means whereby 50 it may be attached to an article, and a decorative face plate having on the back thereof a strap, spaced from said plate and of a width and thickness adjacent the opposite ends thereof to pass 55 between and tension said jaws, the portion of said strap presented toward said plate being of reduced width as compared with the outwardly presented surface thereof, and a block secured thereto of a width to pass between and form abutments engageable by the adjacent ends of each pair of said jaws, whereby relative longitudinal movement of said strap and said jaws is prevented.

5. A decorative buckle embodying therein a 60 clip having two pairs of oppositely disposed rolled

spring jaws, the jaws of each pair being spaced from those of the other pair, and means whereby it may be attached to an article, and a decorative face plate having on the back thereof a strap having its ends bent at substantially right angles and secured to said plate, said strap being spaced from said plate and of a width and thickness adjacent the opposite ends thereof to pass between and tension said jaws, the portion of said strap presented toward said plate being of reduced width as compared with the outwardly presented surface thereof, and a block secured thereto of a width to pass between and form abutments engageable by the adjacent ends of each pair of said jaws, whereby relative longitudinal movement of said strap and said jaws is prevented.

6. A decorative buckle embodying therein a clip composed of spring metal having a body, enlarged ends forming a contact area engageable by the presser foot of a sewing machine, a reduced neck between said ends and said body, and oppositely disposed rolled spring jaws, said necks being positioned beyond said spring jaws, and a decorative face plate having on the back thereof a strap spaced from said plate and of a width and thickness to pass between and tension said jaws, the portion of said strap presented toward said plate being of reduced width as compared with the outwardly presented surface thereof, said strap being provided with abutments engageable with an end of the jaws to prevent relative longitudinal movement of said strap and said jaws.

7. A decorative buckle embodying therein a clip having two pairs of oppositely disposed rolled spring jaws and provided with means whereby it may be attached to an article, and a decorative face plate having on the back thereof and spaced therefrom a strap of a width and thickness to pass between and tension said jaws, the portion of said strap presented toward said plate being of reduced width as compared with the outwardly presented surface thereof, said strap having right angularly bent ends secured to said face plate and having two notches upon opposite sides thereof leaving a central portion of a width to pass between and form abutments engageable by the adjacent ends of each pair of said jaws, whereby relative longitudinal movement of said strap and said jaws is prevented.

8. A decorative buckle embodying therein a clip having oppositely disposed rolled spring jaws and provided with means whereby it may be attached to an article, and a decorative face plate having secured thereto at the back thereof, an arcuate strap having opposite side recesses substantially centrally of the length thereof spaced from said plate and forming opposed abutments engageable by the opposite ends of each jaw, the portion of said strap between said recesses being of reduced width as compared with the outwardly presented surface thereof, and being of a width and thickness to pass between and tension said jaws.

WILLIAM L. MYERS. 65
